UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A TEA-POT.

SPECIFICATION forming part of Design No. 22,369, dated April 25, 1893.

Application filed December 29, 1892. Serial No. 456,708. Term of patent 3½ years

To all whom it may concern:

Be it known that I, CHARLES OSBORNE, a citizen of the United States, residing in the city, county, and State of New York, have invented and produced a new and original Design for Dinner and Tea Sets, of which the following is a specification, reference being had to the accompanying drawing, forming part thereof.

- o The figure is a perspective view of a teapot showing my design.
- o The leading features of the design are the heavy leaf-like borders at the upper and lower extremities of the teapot, the ornamentation at the base of the spout and at the points where the handle connects with the teapot, and the faceted sides of the teapot. The teapot has flattened or faceted sides, the meeting lines of which form rib-like figures on the body of the teapot. Around the upper margin of the body is a heavy garland or wreath-like figure, consisting of spaced clusters of flowers and leaves and connecting tendrils extending from cluster to cluster. The teapot

has claw or upturned feet, from which extend upwardly and in relief, fern-like figures, which also extend laterally and meet between the legs, forming a heavy marginal border around the lower portion of the teapot. At the base of the spout and at the points where the handle connects with the body of the teapot, are flower-like figures having the same general characteristics as the upper and lower marginal borders, the flower-like figures being intermingled with clusters of waving leaves. 25 The cover is given a twisted appearance and terminates at the top in a knob which is ornamented to correspond with the ornamentation of the teapot, that is, the knob represents a cluster of flowers and leaves with drooping 30 branches which lie upon the top of the cover. 35

I claim—

The design for a teapot, herein shown and described.

CHARLES OSBORNE.
